UNITED STATES PATENT OFFICE.

JOHN M. BAKOS, OF SOUTH MILWAUKEE, WISCONSIN.

TOBACCO-SMOKING PIPE.

No. 866,417.

Specification of Letters Patent.

Patented Sept. 17, 1907.

Application filed June 19, 1907. Serial No. 379,698.

To all whom it may concern:

Be it known that I, JOHN M. BAKOS, a citizen of the United States, and a resident of South Milwaukee, in the county of Milwaukee and State of Wisconsin, have 5 invented certain new and useful Improvements in Tobacco-Smoking Pipes; and I do hereby declare that the following is a full, clear, and exact description thereof.

The improvements consist in what is herein shown, 10 described and claimed, the object of the invention being to provide simple, economical tobacco-smoking pipes in each of which there is circuitous travel of smoke from bowl to stem, whereby said smoke is cooled and more or less moisture eliminated therefrom before 15 it is drawn into the mouth of the smoker.

A further object of the invention is to provide for ready cleaning of the pipes.

Figure 1 of the drawings represents a side elevation of a pipe in accordance with my invention partly in 20 section on the lines 1—1 of the next figure, and Fig. 2, a plan view of the pipe partly in horizontal section on the plane indicated by line 2—2 in Fig. 1.

Referring by letter to the drawings, A indicates the bowl, B a the shank and C the mouth-piece stem of a 25 tobacco smoking pipe in accordance with my invention. The bowl and flue-shank are integral and of any suitable material. The lower portion of the flue-shank is horizontally bored and the bore is ordinarily provided with a smooth lining b of metal or other suitable 30 material especially if the pipe be of wood. A smoke-channel c leads from the pipe-bowl into the shank-bore, and flues d, e, f, vertically of the shank communicate with said bore.

In detachable engagement with shank-bore is a plug 35 D having a stem g carrying partitions h so arranged in said bore that the smoke from the pipe-bowl must have travel alternately up and down the flues d, e, respectively on its way to the flue f with which the stem C communicates, the latter flue being enlarged and 40 screw-threaded at its upper end to receive the correspondingly threaded lower end of said stem. It is preferable to have one flue d and two flues e to a set triangularly arranged in the shank B, said shank being recessed at its upper end to provide leads from each 45 updraft flue d to its companion down-draft flues e, the smoke being thus divided and spread over a greater area each time it has descent in the aforesaid shank, whereby the cooling of said smoke is facilitated and a greater condensation of moisture therewith obtained. The 50 upper end of the flue-shank is covered with a sheet i of suitable packing-material confined by a plate j fitting snug in a ferrule k by which said end of the shank is bound, but it would be no departure from my invention to make the plate and ferrule in one piece as a cap for

the aforesaid end of the shank. The plate and packing are shown provided with registering apertures through which to introduce the lower end of the stem C into the flue f of the shank aforesaid, and while I have shown said stem as having screw-thread engagement with said shank-flue it may have wedging fit therein according 55 to the demands of the trade.

From the foregoing it will be understood that draft on the pipe causes smoke from its bowl to enter the horizontal bore of the shank B, ascend a flue d, descend a flue or flues e into space between the partitions h on the plug-stem g then ascend another flue d, descend a flue or flues e into said bore and finally draw up the flue f with which the stem C engages. The up and down draft flues d, e, and the shank-bore partitions, arranged to divide said bore into independent smoke-chambers, 65 may be indefinitely in excess of what is herein shown, and a pipe having but one set of up and down draft-flues d, e, and one suitably arranged shank-bore partition h is within the scope of my invention, although the best results are obtained by a greater number of 70 sets of flues and corresponding divisions of said shank-bore.

Condensation of moisture with the smoke accumulates in the shank-bore and the greater portion of the condensation is removed when the plug D and parts 80 therewith is withdrawn, it being a simple matter to remove the remainder, if any, of said condensation.

I claim:

1. A tobacco-smoking pipe having a bowl-shank provided with a horizontally disposed bore open to the bowl and vertically disposed flues in communication with the bore, certain of these flues being in communication with each other at their upper ends, a removable bore-closing plug having a stem therewith, a partition carried by the stem in position to constitute a cut-off between flues, and a mouth-piece stem having communication with a shank-flue. 85

2. A tobacco-smoking pipe having a bowl-shank provided with a horizontally disposed bore open to the bowl and vertically disposed flues in communication with the bore, certain of the flues being in sets communicating with one another at their upper ends; a removable bore-closing plug having a stem therewith, partitions carried by the stem in position to constitute cut-offs between flues of each set aforesaid, and a mouth-piece stem having communication with the shank-flue. 95

3. A tobacco-smoking pipe having a bowl-shank provided with a horizontally disposed bore open to the bowl and vertically disposed flues in communication with the bore, certain of these flues being in triangular arrangement and communicating one with two others at their upper ends, a removable bore-closing plug having a stem therewith, a partition carried by the stem to constitute a cut-off between the single and twin flues, and a mouth-piece stem having communication with a shank-flue. 100

4. A tobacco-smoking pipe having a bowl-shank provided with a horizontally disposed bore open to the bowl and vertically disposed flues in communication with the bore, a suitable packing on the upper end of the shank closing a recess therein by which communication is established be- 110

tween certain of said flues, means by which the packing is held in place, a removable bore-closing plug having a stem therewith, a partition carried by the stem, in position to constitute a cut-off between flues, and a mouth-piece stem 5 in communication with a shank-flue.

5. A tobacco-smoking pipe having a bowl-shank provided with a horizontally disposed bore open to the bowl and vertically disposed flues in communication with the bore, a suitable packing on the upper end of the shank closing a 10 recess therein by which communication is established between certain of said flues, a plate covering the packing, a

plate-confining ferrule on said shank, and a mouth-piece stem in communication with a shank-flue.

In testimony that I claim the foregoing I have hereunto set my hand at South Milwaukee in the county of Milwaukee and State of Wisconsin in the presence of two witnesses. 15

JOHN M. BAKOS.
